UNITED STATES PATENT OFFICE.

WILLIAM H. CRYAN, OF WOONSOCKET, RHODE ISLAND, ASSIGNOR OF ONE-SIXTH TO
ROMEO J. DANIS, ONE-SIXTH TO WILLIAM F. FOX, ONE-SIXTH TO HAROLD B.
FINDLAY, AND ONE-HALF TO GEORGE F. VERHULST, ALL OF WOONSOCKET, RHODE
ISLAND.

MUFFLER CUT-OUT.

1,424,624.

Specification of Letters Patent.

Patented Aug. 1, 1922.

Application filed October 17, 1918. Serial No. 253,599.

To all whom it may concern:

Be it known that I, WILLIAM H. CRYAN, a citizen of the United States, residing at Woonsocket, in the county of Providence 5 and State of Rhode Island, have invented new and useful Improvements in Muffler Cut-Outs, of which the following is a specification.

This invention relates to internal combustion engines and pertains particularly to the exhaust pipe and the muffler or silencer and to the connections therebetween.

An object of the invention is to provide a cut-out in the exhaust pipe which will allow 15 the exhaust gases, when desired, to pass directly to atmosphere with the least possible resistance and without change in direction.

These and other features of the invention will be described and more fully set forth 20 hereinafter.

The invention consists in the novel construction and arrangement of parts fully described, defined in the appended claims, and illustrated in the accompanying drawings, 25 in which drawings:

Figure 1 is a side elevation of a motor car equipped with my muffler cut-out;

Fig. 2 is an enlarged fragmentary view, partly in section, showing the cut-out in a 30 closed position;

Fig. 3 is a view, similar to Fig. 2, showing the cut-out in an open position;

Fig. 4 is a transverse sectional view taken on the line 4—4 of Fig. 2;

Fig. 5 is a transverse sectional view taken 35 on the line 5—5 of Fig. 3.

Similar reference numerals designate like parts throughout the several views.

Referring to the drawings in detail, 10 represents a motor car having the usual driver's seat 11, steering wheel 12 and hood 13. The hood 13 encases a suitable internal combustion engine (not shown) provided with the usual exhaust pipe 14 and extending 40 rearwardly beneath the hood 13, as shown. A muffler or silencer 15 is securely fastened beneath the rear of the car in any suitable manner as by means of metal straps 16 and is positioned so that the flanged opening 17 is in alinement with the outlet end 14' of the exhaust pipe 14. A connecting pipe 18 preferably of the same diameter as the exhaust pipe 14, is normally held at one end 18' in registry with the outlet end 14' of the exhaust pipe 14 by means of a sliding 55 connection hereinafter described. The opposite end of the connecting pipe 18 extends through the flanged opening 17 and slightly within the muffler 15. The connecting pipe 18 and the flange opening 17 have a sliding 60 or loose fit which permits the opposite or free end 18' of the connecting pipe 18 to be moved out of alinement with the outlet end 14' of the exhaust pipe 14 so as to permit the exhaust gases to pass directly to atmosphere as hereinafter described. Any other suitable means may be provided to permit the movement of the connecting pipe. 65

Rigidly fastened in any suitable manner to the end 14' of the exhaust pipe 14 is a 70 wedge shaped plate 19 provided with retaining grooves 20 on its opposite converging edges. A similar wedge shaped plate 21 is securely fastened to the end 18' of the connecting pipe 18 and is adapted when slid 75 within the grooves 20 to bring the opening in the end 18' of the connecting pipe 18 into registry with the outlet opening 14' of the exhaust pipe 14. The wedge shaped plates 19 and 21 are bent in the form of an arc 80 curved on the radius of movement of the connecting pipe 18, see Figs. 2 and 3. The bottom of the plate 21 is cut away as shown (see Figs. 4 and 5) so that when the end 18' of the connecting pipe 18 is raised out of 85 alinement as shown in Fig. 3, the exhaust gases from the pipe 14 can pass directly to atmosphere. Guide rods 22 are fastened to the bottom of the car in any suitable manner and extend on opposite sides of the connecting pipe 18, preferably near the free end 18', and in engagement therewith. These guide rods 22 prevent longitudinal displacement of the connecting pipe 18 out of its plane of movement. Coil springs 23 are fastened to the plates 19 and 21 by means of the laterally projecting lugs 24 and 25 formed therein, as shown by Figs. 4 and 5, and tend to hold the plate 19 seated in the grooves 20 to prevent accidental displacing 90 of the registering ends 14' and 18'. A wire chain or cord 26 is fastened to the end 18' of the connecting pipe 18 and to a foot operated lever 27 fastened to the floor of the car in a position to be manipulated by the 95 driver of the car when he desires to open the cut-out.

While I have described various details in

connection with my invention, I am aware that many changes in construction and arrangements of parts may be made without departing from this invention. The end of the exhaust pipe may be moved out of alignment with the adjacent end of the connecting pipe or both adjacent ends of the exhaust pipe and connecting pipe may be movable. Such changes as these I aim to include within 10 in the scope of the appended claims.

Having thus described my invention, what I claim as new and desire to secure by Letters Patent of the United States is:—

1. In combination, an exhaust pipe of an internal combustion engine, a connecting pipe for communicating the discharge end of said exhaust pipe with a muffler, and means for moving said connecting pipe away from position opposite the adjacent end of 15 said exhaust pipe to thereby uncover the end of said exhaust pipe and cause the same to discharge the exhaust directly to the atmosphere.
2. In combination, an exhaust pipe of an internal combustion engine, a muffler, a connecting pipe between the discharge end of said exhaust pipe and said muffler, and means for moving said connecting pipe away from position opposite the adjacent end of 20 said exhaust pipe and thereby uncover the end of said exhaust pipe and cause the same to discharge the exhaust directly to the atmosphere.
3. In combination, an exhaust pipe of an internal combustion engine, a muffler, a connecting pipe between said muffler and said exhaust pipe, and means for moving the adjacent end of said connecting pipe out of 25 alignment with the outlet end of said exhaust pipe and thereby uncover the end of said exhaust pipe, and cause the same to dis-

charge in a straight line directly to the atmosphere.

4. In combination, an exhaust pipe of an internal combustion engine, a muffler, a connecting pipe extending into said muffler, a retaining member fastened to the outlet end of said exhaust pipe, and a sliding member secured to the free end of said connecting pipe engaging said retaining member and adapted to hold said connecting pipe in alignment with the outlet of said exhaust pipe.

5. In combination, an exhaust pipe of an internal combustion engine, a muffler, a connecting pipe extending into said muffler, a curved wedge shaped member secured to the outlet end of said exhaust pipe and provided with flanges on its converging sides, a sliding wedge shaped member secured to the free end of said connecting member secured to the free end of said connecting pipe curved on the radius of movement and adapted to be retained by said flanges, and means for moving said sliding member in 65 said flanges.

6. In combination, an exhaust pipe of an internal combustion engine, a muffler, a connecting pipe extending into said muffler, a curved wedge shaped member secured to the outlet end of said exhaust pipe and provided with flanges on its converging sides, a sliding wedge shaped member secured to the free end of said connecting pipe curved on its radius of movement and adapted to 75 be retained by said flanges, means for moving said sliding member in said flanges, and guide members adapted to maintain said connecting pipe in its plane of movement.

In testimony whereof I have hereunto set 80 my hand.

WILLIAM H. CRYAN.
